(57) **CLAIM**

The ornamental design for pair of headphones, as shown and described.

DESCRIPTION

FIG. 1 is a perspective view of a pair of headphones showing my new design.

FIG. 2 is a top view thereof.

FIG. 3 is a bottom view thereof.

FIG. 4 is a left side view thereof.

FIG. 5 is a right side view thereof.

FIG. 6 is a back view thereof; and,

FIG. 7 is a front view thereof.

Broken lines in the drawings are included for the purpose of illustrating an environment and form no part of the claimed design.

1 Claim, 5 Drawing Sheets
